UNITED STATES PATENT OFFICE.

ARTHUR J. BROSEY, OF CHICAGO, ILLINOIS.

CURTAIN STRETCHER.

Original application filed March 19, 1920, Serial No. 367,161. Patent No. 1,485,015. Divided and this application filed January 5, 1924. Serial No. 684,520.

To all whom it may concern:

Be it known that I, ARTHUR J. BROSEY, a citizen of the United States, and a resident of Chicago, in the county of Cook and State 5 of Illinois, have invented certain new and useful Improvements in Curtain Stretchers, of which the following is a specification.

My invention relates to curtain stretcher and the object is to produce an all metal 10 stretcher which is light and durable and easily manipulated to stretch with accuracy and uniformity curtains of different sizes. This application may be considered as a divisional application of my original application 15 Serial No. 367,161.

The various features of construction, arrangement and operation of my invention are illustrated on the accompanying drawing, in which—

20 Fig. 1 is a plan view,

Fig. 2 is an end elevational view showing the stretcher frame in upright position,

Fig. 3 is an enlarged end elevational view 25 of one of the fittings for connecting the stretcher bars,

Fig. 4 is a side elevational view of the fitting,

Fig. 5 is an enlarged view partly in section of the swivel joint of the threaded 30 stretcher bars,

Fig. 6 is an enlarged plan view showing the folding joint for the longitudinal bars,

Fig. 7 is a side view partly in section of such joint connection, and

35 Fig. 8 is a side elevational view of one of the clamps for securing the curtains to the stretcher bars.

The curtain supporting frame comprises the longitudinally extending central or 40 pivot rod 10, the outer longitudinal rods 11 and 12, the central transverse rod 13, and the outer transverse rods 14 and 15. To secure lightness and strength the longitudinal rods are preferably in the form of aluminum 45 tubing, while the transverse rods which are exteriorly threaded are solid but of less diameter than the longitudinal rods. The longitudinal and transverse rods intersect and are relatively adjustable, and at each 50 intersection is applied a fitting which may be constructed as shown in Figs. 3 and 4. The frame is supported on suitable supports such as tripod structures 16 which can be folded into small space. As shown three of 55 such structures are provided, each having a U-shaped seat 17 at its upper end for receiv-

ing the central pivot rod 10, the frame being then free to be swung to either side of the tripod structures during application of a curtain thereto.

Referring to Figs. 3 and 4, each fitting has the longitudinal and transverse clamping heads 18 and 19 provided with passageways 21 and 22 for receiving respectively the longitudinal rods and transverse rods of 60 the frame. In order that the fitting may be more readily applied and adjusted the heads are split. As shown the half 18' of the head 18 is hinged at 23 and at its end has the slotted lug 24 which registers with 65 the lug 25 in which is pivoted the locking pin 26. The threaded end of the pin receives the nut 27, and when the pin is withdrawn the pins may be swung out of the lug 24 to permit the half 18' to be swung open. The head 19 has the half 19' hinged 70 at 28 and provided with the slotted lug 29 which registers with the lug 30 in which 75 latter lug is pivoted the pin 31 having the nut 32.

Three of these fittings *a*, *b* and *c* receive in 80 their passageways 21 the central pivot rod 10, and in the passageways 22 of these fittings are received respectively the transverse rods, 13, 14 and 15. Fittings *d*, *e* and *f* receive the outer longitudinal rods 11 and 85 respectively the transverse rods 13, 14 and 15 at one end. The fittings *g*, *h* and *i* receive the other longitudinal rod 12 and the 90 other ends of the respective transverse rods. When the fittings are applied to the longitudinal rods their passageways 21 will afford sufficient clearance to permit the fittings to be slid along the rods to permit 95 ready adjustment to receive the curtain. After adjustment the fittings are secured in place on the rods by means of the set 100 screws 33.

The outer ends of the transverse rods are threaded and consequently the fittings receiving the rod ends have their passageways 22 correspondingly threaded, and the transverse rods at their outer ends are 105 squared as indicated at 34 to receive a crank or wheel 35 by means of which the rods can be readily turned. Turning of the rods will then cause the longitudinal outer rods to be moved toward or away from the center rod 10. At their centers the transverse rods are 110 journaled in the fittings *a*, *b* and *c* respec-

tively, the passageways 22 of the fittings being unthreaded and smooth, the rods being held against longitudinal displacement by means of collars 36 and 37. The transverse rods could be continuous and their ends provided with right and left threading so that turning of the rods would cause the outer longitudinal rods to be carried toward or away from the pivot rod 10. However I preferably make each transverse rod of two pieces joined together at their inner ends for relative rotational movement. As best shown in Fig. 5 the collars 36 and 37 will be at the ends of the hub 38 which is received in the passageway 22 of the respective fitting to be clamped thereby. The inner ends of the halves of each bar would be bored out as indicated at 39 to receive the cylindrical lugs 40 and 41 on the hub 38 and each lug at its end has a peripheral groove 42 into which extends a pin 43 extended through the wall of the respective rod half. This arrangement will permit the halves of each transverse rod to be independently rotated.

The type of curtain clamping unit I prefer to use is best shown in Figs. 1 and 8. The clamp is formed of a length of sheet metal bent intermediate its ends and expanded at the bend to form a cylindrical sleeve or loop 44, these loops being of sufficient diameter to readily receive the longitudinal and transverse frame rods. At the ends of the limbs 45 and 46 of the clamp segmental plates 47 are secured at their apex ends and extend inwardly, the plates being secured against the inner side of the limbs and presenting convex inner edges for engagement with the scallops or binding of curtains. Normally the limbs of the clamps are sprung apart and a link or belt 48 of wire surrounds the limbs and when shifted outwardly towards the clamping plates the limbs will be brought together and the plates in clamping engagement with a curtain received between them.

When the frame is assembled the center longitudinal rod 10 will be below or behind the transverse rods, but the outer longitudinal rods will be in front or above the transverse rods, as shown in Fig. 2. The outer transverse rods 14 and 15 are first adjusted relative to the longitudinals in accordance with the length of the curtain to be stretched and the outer longitudinal rods are then shifted either inwardly, or outwardly, depending upon the width of the curtain. The clamps on the outer longitudinal and transverse rods are then applied to the curtain C as shown in Fig. 1 and then the wheel 35 is applied to the ends of the transverse rods and the rods turned, the threaded engagement of the rods with the fittings on the outer longitudinal rods then causing such longitudinal rods to be

moved outwardly to stretch the curtain. The frame can be first swung to one side of the tripod structures as shown in Fig. 1 and the upper halves of the transverse rods turned to straighten the curtain edge and to stretch it, and then the frame can be swung over to the other side of the tripods and the other half of the transverse rods turned until the curtain edges are straight and the curtain has been uniformly stretched.

The longitudinal rods are of considerable length and to put them in better form for shipping purposes I preferably joint them at the center so that they may be folded. As shown in Figs. 6 and 7 a bar 49 is inserted into the end of one of the rod halves and secured therein by a pin 50. Into the end of the companion half of the rod is inserted a bar 51 which has the longitudinal slot 52 through which extends the pin 53 which is supported by the half so that the half and the bar may move relatively. The outer end of the bar 49 has the bifurcation or slot 54 and the outer end of the bar 51 has a similar slot 55. A joint link 56 engages in the slots and is pivoted to the respective bars by pins 57 and 58. When the rod halves are brought together and both in engagement with the bar 49 the rod will be continuous and unbendable. However when the shiftable half is shifted outwardly as shown in Fig. 6 the joint link 56 will be exposed and the rod halves can then be folded to be brought together. The pin 53 limits the outward movement of the shiftable rod half. The shiftable half is provided with the opening 59 through which the set screw 33 of the fitting a, d or g may be inserted to set against the bar 49 after the rod halves have been brought together, and the halves will then be locked against separation.

I thus produce a simple and very efficient curtain stretcher structure on which curtains can be quickly and readily applied and uniformly stretched. By using the improved clamps with their wide jaw plates and convex edges the curtains are securely clamped and prevented from tearing when the curtain is under tension, and the jaw plates by engaging against the binding of the scallops will preserve the proper curvature of the curtain edges. It is not necessary to bend or stoop when applying the curtains for stretching them owing to the central pivotal support of the frame. The stretcher can be quickly adjusted for different sizes of curtains from the smallest to the largest. The frame rods being of aluminum the structure is very light, and on account of the folding longitudinal rods the entire structure can be compactly arranged for storage or shipment.

I do not desire to be limited to the exact construction and arrangement shown and

described as modifications can be made which would still come within the scope of the invention.

I claim as follows:

- 5 1. In a curtain stretcher, the combination of a central longitudinal rod, a central transverse rod, a fitting secured to said central longitudinal rod at the center thereof, said central transverse rod being journaled in 10 said fitting at its center but locked against longitudinal movement, and outer longitudinal rods at each side of said center longitudinal rod, a fitting secured to each outer longitudinal rod at its center, said center 15 transverse rod being threaded, said outer longitudinal rod fittings receiving said threaded center transverse rod, an outer transverse rod at each side of said center transverse rod, fittings adjustable longitudinally 20 on the ends of the center longitudinal rod, said outer transverse rods being journaled at their centers in said fittings to be rotated but to be locked against longitudinal movement, said outer transverse rods being 25 threaded, and fittings adjustable on the outer ends of said outer longitudinal rods having threaded passageways for receiving the corresponding outer transverse rods, turning of said transverse rods causing 30 movement of said outer longitudinal rods toward or away from said center longitudinal rod.
2. In a curtain stretcher, the combination of a center longitudinal rod, center transverse rods extending in opposite directions from the center of said longitudinal rods, a fitting secured to said longitudinal rod at the center thereof, said transverse center rods being swiveled at their inner ends in 35 said fittings to be independently rotatable, said transverse rods being threaded at their outer ends, an outer longitudinal rod at each side of said center longitudinal rod, fittings secured to the centers of said outer longitudinal rods and threadedly receiving the 40 respective center transverse rods, means for supporting from said outer longitudinal rods the sides of a curtain to be stretched, means for turning said center transverse 45 rods to thereby effect movement of either 50 outer longitudinal rods toward or away from the center longitudinal rod to transversely stretch the curtain, and outer transverse rods longitudinally adjustable on said center longitudinal rod, and means for supporting from said outer transverse rods the ends of the curtain to be stretched. 55
3. In a curtain stretcher, the combination of a center longitudinal rod, supports for said rod for holding it in horizontal position, a center transverse rod and outer transverse rods above said center longitudinal rod, fittings rotatable on said center longitudinal rods and receiving said transverse rods at their centers, said transverse rods being threaded and being rotatable in said fittings but locked against longitudinal movement thereby, other fittings threadedly receiving the outer ends of said threaded transverse rods and extending upwardly 60 from said transverse rods, and outer longitudinal rods received in said fittings on said transverse rods, turning of said transverse rods causing said outer longitudinal rods to be shifted toward or away from the center longitudinal rod. 65
4. In a curtain stretcher, the combination of a center longitudinal rod and an outer longitudinal rod at each side thereof, said rods being jointed at their centers whereby they may be folded together, a center transverse rod, fittings for engaging with said longitudinal rods at their joints to lock said joints, said center transverse rod being journaled at its center in the fitting of the center longitudinal rod whereby said transverse rod may be rotated, said transverse rod being threaded at its ends and the fittings of the outer longitudinal rods receiving said threaded ends whereby turning of said transverse rod will cause adjustment of said outer longitudinal rods toward or away from the center longitudinal rod, and outer transverse rods adjustable longitudinally on 70 said longitudinal rods. 75
